United States Patent

Des. 241,161
Patented Aug. 24, 1976

241,161

RECORD PLAYER

Shigenori Tomioka, Tokyo, Japan, assignor to Japan
Metals & Chemicals Co., Ltd., Tokyo, Japan

Filed July 29, 1974, Ser. No. 492,547

Term of patent 3½ years

Int. Cl. D14—01

U.S. Cl. D56—4 R

FIG. 1

FIG. 2

FIG. 3

FIG. 4

FIG. 1 is a perspective view of a record player showing my new design;

FIG. 2 is a front elevational view;

FIG. 3 is a rear elevational view; and

FIG. 4 is a bottom plan view.

The bottom cover is lined to indicate transparency.

I claim:

The ornamental design for a record player, substantially as shown and described.
